COMBINED WATER CLOSET AND LAVATORY

John L. Campbell, Flourtown, Pa., assignor to
Kelsey-Hayes Company, Romulus, Mich.

Filed Jan. 19, 1973, Ser. No. 325,027

Term of patent 14 years

Int. Cl. D23—02

U.S. Cl. D23—49

FIG. 1 is a perspective view of a combined water closet and lavatory embodying my new design;

FIG. 2 is a top plan view thereof;

FIG. 3 is a side elevational view thereof; and
FIG. 4 is a front elevational view thereof.

I claim:

The ornamental design for a combined water closet and lavatory, substantially as shown.
